UNITED STATES PATENT OFFICE.

JOHN ANDREWS, OF MARLBOROUGH, MASSACHUSETTS, ASSIGNOR TO
GEORGE J. ANDREWS, OF SAME PLACE.

DESIGN FOR A SASH-LIFT.

SPECIFICATION forming part of Design No. 23,728, dated October 23, 1894.

Application filed September 18, 1894. Serial No. 523,420. Term of patent 14 years.

To all whom it may concern:

Be it known that I, JOHN ANDREWS, a citizen of the United States, residing at Marlborough, in the county of Middlesex and State of Massachusetts, have invented and produced a new and original Design for Sash-Lifts; and I do hereby declare the following to be a full, clear, and exact description of the invention, such as will enable others skilled in the art to which it appertains to make and use the same.

This invention refers to a design for a sash-lift, the object being to improve its outline and general appearance, and it consists in the design hereinafter described and claimed.

In the annexed drawings illustrating my design: Figure 1 is a perspective view of my newly designed sash-lift. Fig. 2 is a cross-sectional elevation of the same.

Like letters denote like parts in both figures.

A denotes the main body of the design for a sash-lift, which body is of a general rectangular form. On the under side, along one

edge, is a flange B, so shaped that the under surface of the body A, is concavely-curved from edge to edge the sharpest part of the curvature being on the flange B. The outer face D of the flange B is at right angles to the upper face of body A. The upper face of body A is a flat surface from the center of which projects at right angles the finger piece C, thereby dividing the upper face of body A into two parts a, a'. The edge of piece C is rounded as shown. The surfaces a, a' are neatly ornamented with depressions b b, there being four of these on each surface, placed at right angles to each other, as shown, around central circular openings c.

What I claim is—

The design for a sash-lift substantially as herein shown and described.

In testimony whereof I affix my signature in presence of two witnesses.

JOHN ANDREWS.

Witnesses:

MARY E. WOODBURN,

JOHN R. BULLARD.
